UNITED STATES PATENT OFFICE.

EVERETT BARD, OF WATER VALLEY, KENTUCKY.

PENCIL-CLIP.

1,321,878.

Specification of Letters Patent. Patented Nov. 18, 1919.

Application filed April 2, 1919. Serial No. 286,960.

To all whom it may concern:

Be it known that I, EVERETT BARD, a citizen of the United States, residing at Water Valley, in the county of Graves and 5 State of Kentucky, have invented a new and useful Pencil-Clip, of which the following is a specification.

This invention relates to improvements in 10 clips for retaining pens or pencils in the pocket of the user, the primary object of the invention being to provide an improved clip that is particularly adapted for use with pockets having flaps and which will hold the pencil in the pocket in such position that the 15 top of the pencil will not project above the edge of the pocket, whereby the flap of the pocket may be fastened over the pencil without distortion of the flap.

A further object of the invention is to 20 provide a clip of the character set forth which will permit the use of an eraser on the end of a pencil, and which is extremely simple in construction, economical to manufacture and very reliable in its action.

25 With the foregoing and other objects in view, which will appear as the description proceeds, the invention consists in the novel features of construction and combination of parts which will be more fully described 30 hereinafter and particularly pointed out in the claims.

In the drawings accompanying and forming part of this specification,

Figure 1 is a vertical section of a pocket 35 having a flap, illustrating one form of the improved clip applied thereto and retaining a pencil in said pocket, the flap being shown buttoned over the clip;

Fig. 2 is a plan view of the clip and pencil 40 shown in Fig. 1;

Fig. 3 is a perspective view of the clip, illustrating its application to a pen, the latter being shown in dot and dash lines;

Fig. 4 is a side elevation of a modified 45 form of the clip, shown as applied to a pen, the latter being broken away at its lower end; and

Fig. 5 is a side view at right angles to Fig. 4.

50 The same characters of reference designate the same parts in the different figures of the drawings.

Pen and pencil holding clips as heretofore provided have been so constructed that 55 the end of the pencil or pen projects some distance above the edge of the pocket, and

therefore when such clips are used with pockets having flaps, such for instance as military uniforms, the flap is caused to bulge out and present a very unsightly appearance. 60 Military discipline requires that everything in dress be neat and tidy, and therefore a soldier must either run the chance of being reprimanded for the untidy appearance of his coat or shirt flap when his pen or pencil 65 is held by means of a clip, or must carry his pen or pencil loose in his pocket. In the latter case the pen or pencil will work down into a horizontal position, and as the pencil is straight and the tight-fitting uniform is 70 curved the wearer of the uniform is subjected to considerable discomfort. The object of the present invention, therefore, is to overcome the difficulties referred to and to provide a very efficient and cheap type of 75 pencil holder or clip.

In the structure shown in Figs. 1 to 3 of the drawings, the clip is formed of a single piece of spring wire bent upon itself to form a pair of parallel semi-circular portions 2 adapted to partly encircle the pencil, said portions being connected by a straight portion 3. At the end of the second semi-circular portion the wire is bent outwardly to form a second straight portion 4 extending in a direction parallel with the portion 3. At the end of the portion 4, the wire is bent at right angles to said portion and slightly curved or bulged outwardly, as at 5, to adapt it to conform in a general way to 90 the curvature of a pen or pencil at the side opposite the points engaged by the two parallel portions 2. At a point approximately opposite the center of the curved portions 2, the portion 5 is bent downwardly 95 and bulged outwardly, and then tapered in toward the lower curved member 2, as shown at 6, the end of the wire being then turned over upon itself, as at 7, to provide a blunt end to protect the clothing from being torn 100 thereby. In this form the device may be manufactured at a very small cost, and while it may be used in connection with either a pen or pencil, it is particularly well adapted for use with a pencil having an eraser at its 105 end, since the open end of the clip permits free use of the eraser without interference.

In the form shown in Figs. 4 and 5, the clip is formed from a piece of spring sheet material that is stamped into T-shaped 110 form, the cross arms 8 being curved to conform to the curvature of the pen or pencil.

At a short distance from the arms the body portion is bent over upon itself to form a spring tongue 9 opposite the opening between the ends of the curved members 8.

5 In the use of the device shown in Figs. 1 to 3, the clip is placed on the pen or pencil so that the portion 5 thereof is approximately in line with the extreme end of such pen or pencil, whereby, as clearly shown in 10 Fig. 1, when the pencil is placed in the pocket and the clip engages the front wall 10 of the pocket there is nothing to project above the upper edge of such wall but the thickness of the wire, so that the flap 11 can 15 be buttoned over the pencil and clip. It will be readily seen that in the use of the device shown in Figs. 4 and 5 also, the only thing that will be above the edge of the front wall of the pocket is the thickness of 20 the material of the clip. In either form of the device, therefore, the flap will lie down neatly in place without any appreciable bulge.

From the foregoing it will be observed 25 that in both forms of the device herein illustrated, I have provided a pair of spring portions extending approximately in parallel relation, one of which portions is adapted to grip the pen or pencil while the other 30 is adapted to exert pressure on the side of the pencil opposite to said gripping portion, and that said spring portions form between them a loop adjacent to the extreme end of the pen and which loop is adapted to engage the upper edge of a pocket.

Another advantage that may be mentioned 40 for the improved clip is the fact that the same spring action that clamps the garment to the pencil also clamps the clip on the pencil, so that in the structures herein illustrated there is no spring action tending to overcome another spring action, as in all of the devices with which I am familiar.

While I have described in detail the struc-

tures herein illustrated, it is to be understood that I do not thereby limit my invention to the precise features of construction shown, as I am aware that many mechanical changes may be made therein without departing from the spirit and scope of the 50 invention as set forth in the appended claims.

Having thus described my invention, what I claim is:

1. A device of the class described, comprising a member extended upon itself to form a pair of curved coöperating gripping portions adapted to partly encircle a pen or pencil between them and a portion extending in approximate parallelism with such gripping portions and adapted to form a clamp adapted to bear against the pen or pencil at the unencircled portion thereof thereby to clamp the same between such coöperating portions, the gripping and clamp- 65 ing portions forming between them an overlying loop adapted to rest on the upper edge of a pocket adjacent to the end of the pen or pencil.

2. A device of the class described, comprising an integral member formed of wire bent to provide a pair of curved parallel portions connected by a straight portion, a straight portion extending from the end of one of said curved portions in a direction 70 parallel with said first straight portion, a portion at an angle to said second straight portion and slightly curved in a direction 75 opposite to said first mentioned curved portions, and a portion extending downwardly 80 from said slightly curved portion.

In testimony that I claim the foregoing as my own, I have hereto affixed my signature in the presence of two witnesses.

EVERETT BARD.
